Application November 25, 1938, Serial No. 242,215

6 Claims. (Cl. 122—478)

This invention relates to the generation and superheating of vapors and more particularly pertains to steam generators and superheaters.

The invention provides a combination of a forced circulation boiler and a natural circulation boiler with means for controlling the temperature or the degree of superheat, of the steam.

The invention will be understood from the following description considered in connection with the accompanying drawing, the single figure of which illustrates diagrammatically a steam generator embodying the invention.

Referring to the drawing, reference character 10 designates the setting of a steam generator which encloses a forced circulation steam generating section at its right hand end as viewed in the drawing, a natural circulation steam generating section at its left hand end, and a superheating section in the forced circulation section.

Feed water is supplied to the generator through line 11 to a feed pump 12 which delivers it to an economizer 13 in a flue 14, the inlet of which connects with the setting at a point between the forced and natural circulation sections of the generator. From the economizer the water flows through line 15 to a header 16 at the upper right hand end of the generator and through a plurality of rows of steam generating tubes 17, the inlet end portions of which, as shown, are looped to define the major portion of a furnace chamber 18 which is fired by a plurality of fuel burners 19 adapted to burn pulverized coal, oil, or gas, or a combination of these fuels. One or more burners 19 may be used to fire the furnace 18. Intermediate the chamber 18 and the flue 14, the steam generating tubes are formed into a plurality of return bend loops, and the water flowing therethrough and the steam generated therein is delivered to a steam and water drum 20 of the natural circulation boiler section. A bank of steam generating tubes 21 connects the upper drum 20 and the lower drum 22 which is shown as located somewhat to the right of a position immediately below the upper drum 20, but it may be disposed in other positions if desired. Tubes 23 connecting the upper and lower drums 20 and 22 define with the bank of tubes 21, a furnace chamber 24 which is fired by a plurality of fuel burners 25 like, or similar to, the burners 19. One or more burners 25 may be used.

Steam in the drum 20 is conducted through line 26 to the inlet header 27 of a superheater 28 which is disposed in the tube bank 17 between the furnace 18 and the flue 14. The superheated steam flows into outlet header 29 and through

line 30 to the point of use. The superheater may be located in any suitable position in the forced circulation boiler.

The natural circulation section of the generator will always be in use during operation of the generator. To maintain a constant, or substantially constant, level of water in the drum 20, water must be entering the drum 20 with steam from the forced circulation section of the generator. For example, if 110,000 pounds of feed water an hour is delivered to the economizer 13 for passage through the forced circulation section of the generator, furnace 18 will be so operated that approximately 100,000 pounds per hour will be evaporated, and the remaining 10,000 pounds per hour will be delivered to the drum 20 and will be evaporated in the natural circulation section of the generator by suitable operation of furnace 24. With a constant water level in drum 20, water will always be present in the coils of the forced circulation section, so that all superheating will be effected in the superheater only.

The steam pressure and the degree of superheat is controlled by varying the relative rates of combustion in the furnaces 18 and 24. Variations in the rate of firing of the natural circulation section furnace 24 will take care of or provide for, variations in load on the generator, while variations in the rate of firing of furnace 18 will provide control of superheat temperature and will also provide for variations in load in conjunction with the firing of furnace 24. For example, if it is desired to lower the degree of superheat, the rate of firing of furnace 18 will be decreased which will not only lower the steam temperature but will also reduce the rate of evaporation of water in the bank of tubes 17. To compensate for this reduced evaporation, the rate of firing of furnace 24 is increased to the extent necessary to take care of the load and to maintain the level of water in the drum 20. Conversely, if it is desired to increase the degree of superheat, the rate of firing of furnace 18 is increased which will raise the steam temperature and will at the same time increase the rate of evaporation in tube bank 17, to compensate for which the rate of firing of furnace 24 is reduced. In this manner, the steam temperature may be varied as desired with constant or variable load, or the temperature may be maintained constant or substantially so, over a wide load range. The rate of firing of the furnaces 18 and 24 may be accomplished by varying the intensity of firing of the burners or by varying the number of burners in

operation. The control of the burners and the feed pump 12 and the interrelationship of their individual operation is preferably effected automatically, but such control may be effected manually.

Ordinarily, the total steam generating surface in the forced circulation section will be greater than the corresponding surface in the natural circulation section, and it may be disposed in any suitable or desired position without regard to gravitation. Circulating pumps are not required for the generator, nor is water injection into the superheater necessary. The water flow to the generator is controlled simply by the water level in the steam and water drum 20, although supplementary devices based on changes in steam demand or rise in temperature of the fluid entering the steam drum may be used, if desired.

The water in either or both of the drums 20 and 22 of the natural circulation section may be blown down to reduce the concentration of salts in the generator.

It will be apparent that changes may be made in the form, location and relative arrangement of the several parts of the generator and superheater disclosed without departing from the principles of the invention. Hence, it will be understood that the invention is not to be limited excepting by the scope of the appended claims.

What is claimed is:

1. A vapor generator comprising a setting, a forced circulation vapor generating section in the setting, a natural circulation vapor generating section in the setting and into which vapor and liquid from the forced circulation section is discharged to supply the liquid therefor, and independent means for firing each section, the arrangement being such that the gases from each firing means flow in substantial heat exchange relationship with but one of said sections.

2. A vapor generator comprising a setting, a forced circulation vapor generating section in the setting, a natural circulation vapor generating section in the setting, a vapor and liquid drum common to both sections, independent means for firing each section, the arrangement being such that the gases from each firing means flow in substantial heat exchange relationship with but one of said sections, and a superheater having tubes in heat exchange relationship with the gases produced in firing the forced circulation section.

3. A vapor generator comprising a setting, a forced circulation vapor generating section in the setting, a natural circulation vapor generating section in the setting comprising upper 5 and lower drums and vapor generating tubes connecting the drums, the vapor and liquid outlet of the forced circulation section being connected to said upper drum, and independent means for firing each section, the arrangement being such that the gases from each firing means flow in substantial heat exchange relationship with but one of said sections.

4. A vapor generator comprising a setting, a forced circulation vapor generating section in the setting comprising a bank of vapor generating tubes, a furnace, and a feed pump for delivering liquid to said tubes, a natural circulation vapor generating section in the setting comprising upper and lower drums, vapor generating tubes connecting the drums, and a furnace, the vapor and liquid outlet of the forced circulation section being connected to said upper drum, a superheater having tubes disposed in heat exchange relationship only with the gases produced in the furnace of the forced circulation section, and burners for firing each furnace, the arrangement being such that the gases from each firing means flow in substantial heat exchange relationship with but one of said sections.

5. A steam generator comprising a setting, a forced circulation steam generating section in the setting, a natural circulation steam generating section in the setting, the arrangement being such that the forced circulation section 30 discharges steam and water into the natural circulation section, a superheater in the forced circulation section, and one or more fuel burners for firing each section, the sections being disposed so that each is out of substantial heat exchange relationship with the gases produced by the burners for firing the other section.

6. A vapor generator comprising a setting, a forced circulation vapor generating section in the section, a natural circulation vapor generating section in the setting and into which vapor and liquid from the forced circulation section is discharged to supply the liquid therefor, a superheater in the forced circulation section, and independent means for firing each section, the arrangement being such that the gases from each firing means flow in substantial heat exchange relationship with but one of said sections.

JOHN BLIZARD.
